UNITED STATES PATENT OFFICE.

JOSEPH W. SHARP, OF PHILADELPHIA, PENNSYLVANIA.

GAS BURNER.

Application filed October 27, 1926. Serial No. 144,556.

The present invention relates to gas burner attachments for coal burning stoves and furnaces, and is an improvement on Patent #1,466,763, granted to me on September 4, 5 1923.

The primary object of the present invention is to provide a gas burner attachment for coal burning stoves and furnaces, embodying a novel heating arrangement whereby the gas may be preheated before passing to the burner of the device.

A further object of the invention is to provide an improved type of heater for gas burners of the class described, and which heater serves as a support for the burners and heat distributing elements of the device.

A still further object of the invention is to provide an improved type of heater for gas burners as aforementioned, which will be extremely durable and efficient when in use, and which heaters are of such construction as to permit of the ready installing thereof within the fire boxes of existing types of coal burning stoves and furnaces.

Other objects and advantages of the invention will be apparent during the course of the following detailed description, taken in connection with the accompanying drawing forming a part of this specification, and in 30 which drawing:

Figure 1 is a longitudinal sectional view thru the fire box of a conventional type of coal burning cooking stove, and showing the improved burner associated therewith.

Figure 2 is a longitudinal section thru the heater of the attachment, taken on line 2—2 of Figure 1.

Figure 3 is a bottom plan view of a modified form of the gas burner attachment for use in connection with various sizes and shapes of stoves and furnaces.

Figure 4 is an enlarged fragmentary section taken on line 4—4 of Figure 3.

Referring to the drawing in detail, and 45 wherein similar reference characters designate corresponding parts throughout the several views, the letter A designates a conventional type of coal burning cook stove, and B the improved gas burner attachment embodying an adjustable supporting bracket C, burners proper D, and a preheating chamber E.

The stove A is of the usual construction, and includes a fire box 5 provided with the 55 usual fire brick lining 6 and the ash pit 7.

The ash pit 7 is provided with the usual bottom wall 8 and the front door opening 9 whereby the ashes may be readily removed from the ash pit.

In applying the improved gas burner attachment to the stove, the usual grate and grate bars are removed from the stove, and which removal of the grate and grate bars provides ample space for mounting of the improved burner attachment B.

Referring now to the improved burner attachment B, the same embodies a substantially rectangular shaped partition plate 10 which is preferably formed of fire clay or some other suitable refractory material, and which plate is disposed horizontally below the fire brick lining 6 with its marginal edges snugly engaging the inner faces of the lower portion of the fire box 5. Thus it will be seen that this partition plate 10 forms a 75 division between the fire box 5 and ash pit 7 in a manner for preventing ready circulation of air from one to the other.

The support C, and which is arranged in the ash pit 7, embodies a pair of vertically adjustable end brackets 11 which are preferably connected at their upper ends by means of strips 12 which extend longitudinally of the ash pit 7. These end brackets 11 may be adjusted vertically by means of set screws 85 13 fitted thru the lower portions of the brackets and bearing at their lower ends upon the upper side of the bottom wall 8 of the ash pit.

Referring now to the burners proper D, 90 and two of which are shown in the drawing, each embodies a vertically extending tube 15 provided at its upper end with a burner cap 16 disposed above the partition plate 10. The lower end of each of the tubes 15 is provided with a suitable mixing chamber 17 which may be provided with suitable operating means for controlling the amount of air and gas passing thru the tube 15 to the burner cap 16.

The heater E, and which is preferably formed of cast metal, is of rectangular shape in plan and of a size equal to that of the partition plate 10. This heater is of hollow formation for providing a relatively flat 105 chamber 18 provided with flat upper and lower walls 19 and 20 respectively. Provided at the longitudinal center of the heater, are spaced vertically extending conduits 18' which connect the upper and lower walls 110

of the heater, and the openings thru the conduits are adapted to align with openings 21 provided in the partition plate 10. These aligning openings 21 and conduits 18', are 5 adapted to receive the vertically disposed tube 15 of the heater E, with the cap 16 extending above the plate 10 into the fire box 5, and with the mixing chambers 17 at the 10 lower ends of the tubes disposed in the ash pit 7 below the lower wall 20 of the heater.

The heater E is adapted to be supported in a horizontal position by means of the adjustable support C, with the partition plate 10 resting upon the upper side of the heater 15 and in surface contact with the top face of the upper wall 19. By so having the plate 10 and heater E of a size equal to the inner 20 dimensions of the fire box 5, it will be seen that the plate and heater may be readily slipped downwardly into the fire box upon removal of the stove top 50.

Arranged in the fire box 5, and positioned one over each of the burner caps 16, are heat distributing burner hoods or mufflers 22 which are also formed of fire clay or some other suitable refractory material. As illustrated in Figure 1, these hoods 22 are of substantially rectangular shape, and include the side walls 23, end walls 24, and a 30 top wall 25. These walls 23, 24 and 25 are provided with relatively small perforations thru which the heat and flame from the burner caps 16 is projected and allowed to circulate within the fire box 5. The lower 35 ends of the hoods 22 are left open, and by observing Figure 1 it will be seen that the lower edges of the walls 23 and 24 rest upon the upper flat surface of the partition plate 10.

40 Suitably connected at one end with the lower wall 20 of the heater E, are substantially U-shaped feed pipes 26 having their opposite upwardly turned arms connected with the lower end of the mixing chamber 45 17 of the burners B. Suitable gas cocks 27 are provided in each of the feed pipes 26 for controlling of the flow of gas from the chamber 18 to the respective burners B. These gas cocks 27 may be operated independently, or by means of a suitable link 50 arrangement as shown by dotted lines in Figure 1. By observing Figure 1, it will be seen that the burners D are supported by the heater E thru the U-shaped feed pipes 26.

55 A suitable supply pipe 30 is connected with the chamber 18 at one end of the heater, and may extend thru the opening 9 and be connected with any suitable source 60 of gas supply.

65 Thus it will be seen that gas entering thru the supply pipe 30 is allowed to circulate thru the chamber 18 and be preheated before passing thru the depending U-shaped feed pipes 26 into the burners D. It will

readily be apparent the manner in which the heater E may be heated by reason of intimate contact at its upper surface with the plate 10 which is subjected to the heat created within the fire box 5.

70 Referring to the form of the invention as illustrated in Figures 3 and 4, and which type is adapted for use in those types of stoves and furnaces provided with round fire boxes, the plate 30' and heater E' are of 75 circular formation and are adapted to support circular shaped hoods or mufflers 22'. The chamber 31 of the heater E' is provided with the vertically extending conduits 32 which align with openings 33 provided in 80 the plate 30' for receiving the vertically extending heater proper D'. Connected at the axial center of the lower wall 34 of the heater E', is a depending feed pipe 35 having a cross 36 connected at its lower end with the radially extending arms of the cross connected at their outer ends with the 85 lower ends of the respective burners D'. Thus it will be seen that a substantially U-shaped connection is made between each of the burners D' and the chamber 31, and that the burners are supported solely by the feed pipe 35. A suitable supply pipe 45' provided with a gas cock 37, may be connected with the heater E' for the admission of gas 90 into the chamber 31 of the heater.

95 By so having the partition plates 10 and 30' arranged in surface contact throughout the entire upper surface of their respective heaters E and E', it will be seen that upon heating of the plates, that their respective heaters will be heated throughout their entire upper surfaces.

100 From the foregoing description it will be apparent that a novelly constructed gas burner attachment for coal burning stoves and furnaces has been provided, embodying an improved heating arrangement whereby the gas is preheated prior to its passage into the burners proper of the attachment.

105 Changes in detail may be made to the specific form of the invention herein shown and described, without departing from the spirit of the invention or the scope of the following claims.

110 I claim:

115 1. The combination with a coal burning stove including a fire box and an ash pit provided with a bottom wall, of a gas burner attachment therefor including a supporting bracket arranged in the ash pit and resting upon the bottom wall thereof, a hollow heater supported horizontally by said bracket, a plate of refractory material resting in surface contact upon the upper face of the heater 120 and forming a partition between the fire box and ash pit of the stove, burner tubes extending vertically thru the heater and plate and projecting into said fire box, feed pipes 125 connecting said burner tubes with the hollow 130

low heater, and a gas supply pipe connected with the heater and extending from the ash pit of the stove.

2. The combination with a coal burning stove including a fire box and an ash pit provided with a bottom wall, of a gas burner attachment therefor including a supporting bracket arranged in the ash pit and resting upon the bottom wall thereof, a hollow heater supported horizontally by said bracket, and provided with vertically arranged conduits opening at the upper and lower sides of the heater, a plate of refractory material resting in surface contact upon the upper face of the heater and forming a partition between the fire box and ash pit of the stove, said plate being provided with openings aligning with the conduits provided in the heater, vertically disposed burner tubes extending freely thru the conduits and aligning openings of said plate and projecting into said fire box, feed pipes connecting the burner tubes with said hollow heater and serving as a support for the tubes, a gas supply pipe connected with the heater, and means for controlling the flow of gas to the burner tubes.
3. The combination with a coal burning stove including a fire box and an ash pit, of a gas burner attachment therefor including a relatively flat hollow heater, means for supporting the heater horizontally within the ash pit of the stove, a plate of refractory material resting in surface contact upon the upper face of the heater and forming a partition between the fire box and ash pit of the stove, burner tubes extending vertically thru the heater and plate and projecting upwardly into the fire box, U-shaped feed pipes connected at one end with the lower wall of the hollow heater and having their opposite ends connected with the burner tubes, means for controlling the flow of gas thru each feed pipe to its respective burner tube, and a gas supply pipe connected with the heater and projecting exteriorly of the stove.
4. The combination with a coal burning stove including a fire box and an ash pit provided with a bottom wall, of a gas burner attachment therefor including a relatively

flat hollow heater provided with vertically arranged conduits, means for supporting the heater in horizontal spaced relation above the bottom wall of the ash pit, a plate of refractory material resting in surface contact upon the upper face of the heater and forming a partition between the fire box and ash pit of the stove, said plate being provided with openings aligning with the conduits provided in the heater, burner tubes extending freely thru the conduits and aligning openings in said plate and projecting upwardly into said fire box, perforated hoods arranged over the upwardly projecting ends of the burner tubes and resting upon said plate, U-shaped feed pipes arranged in the space below said heater, having one arm connected with the lower wall of the hollow heater and having their opposite arms connected with the burner tubes below the lower wall of the heater, valves arranged in each feed pipe, and a gas supply pipe connected with the heater and extending exteriorly of the stove.

5. The combination with a coal burning stove including a fire box and an ash pit provided with a bottom wall and having a door opening, of a gas burner attachment thereof including a supporting bracket arranged in the ash pit and resting upon the bottom wall thereof, a relatively flat hollow heater of a size and shape in plan equal to the smallest dimensions of the fire box, supported horizontally upon said bracket in spaced relation above the bottom wall of the ash pit, a plate of refractory material and of a size in plan equal to that of the heater, resting in surface contact upon the upper face of the heater and forming a partition between the fire box and ash pit of the stove, burner tubes extending vertically thru the heater and plate and projecting into the fire box, feed pipes arranged in the space below the heater and connecting each burner tube with the heater, means for controlling the flow of gas to the burner tubes, and a gas supply pipe connected with the lower wall of the hollow heater and extending thru a door opening of the ash pit.

JOSEPH W. SHARP.
